UNITED STATES PATENT OFFICE.

WALTER H. WHITTIER, OF GRAND RAPIDS, MICHIGAN, ASSIGNOR TO KELVINATOR CORPORATION, OF DETROIT, MICHIGAN, A CORPORATION OF MICHIGAN.

REFRIGERATOR.

Application filed May 14, 1927. Serial No. 191,322.

This invention relates to refrigerator cabinets.

An object of the invention is to provide a refrigerator with a single door arranged to close or expose both a food storage chamber and a chamber housing a refrigerating medium.

A further object of the invention resides in the manner of supporting and securing the ice supporting partition in a refrigerator structure.

Another object of the invention is to provide a durable refrigerator construction which can be manufactured for a minimum cost.

These and other objects of the invention will be more apparent as the description progresses in which like characters refer to like parts in the drawings illustrating a preferred embodiment of the invention, in which:

Fig. 1 is a perspective view of a refrigerator cabinet showing one of the refrigerator doors in open position.

Figs. 2 and 3 are sectional detailed views through the refrigerator door structure taken substantially on the lines 2-2 and 3-3 of Fig. 1, and

Fig. 4 is a vertical sectional view of the refrigerator taken substantially on the line 4-4 of Fig. 1 but with the door closed.

The refrigerator cabinet structure consists generally of a front wall 10, top wall 11, bottom wall 12, side walls 9, and a rear wall 13, defining an interior chamber which is divided by vertical and horizontal partitions into a plurality of food storage compartments 14 and an ice compartment 15. The front wall of the refrigerator is preferably provided with two openings which are closed by the doors 17 and 18, the door 17 closing the opening to the ice chamber 15 as well as to the food storage compartment 14 immediately below the ice chamber. Due to the excessive loads, such as large blocks of ice which are continually placed in the ice chamber, it is quite necessary that the bottom wall of the ice chamber should be rigidly supported within the cabinet to prevent the bottom wall from sagging. In the construction shown in the accompanying drawings a supporting member 20 is preferably secured to one of the end posts and to the middle post of the cabinet structure, and extends transversely across the door opening. This frame member is

provided with a groove 21 extending longitudinally thereof substantially the full length of the frame member for receiving one end of a supporting angle bracket 22. A partition 26 generally constructed of wood is supported at its front end on an inwardly extending end 25 of the bracket and the rear end of the partition is supported on a bracket 27 which is fastened to the rear wall 13 of the refrigerator cabinet structure. It will be noted that this partition is thus rigidly supported along its front and rear edges and consequently it will not sag and is strong enough to support heavy loads, such as large blocks of ice which are placed in the ice compartment.

The door 17 is constructed and arranged to fit this particular cabinet construction. It will be noted that the outer face of the frame member 20 is set in from the face of the front wall of the refrigerator cabinet and the refrigerator door lining is formed of two sections spaced sufficiently to form a recessed portion 27a that will straddle the frame member when the door is closed. Such a construction permits the construction of a door having a maximum amount of heat insulation assembled therewith, without requiring the door to be unnecessarily projected from the front face of the cabinet. Suitable sealing strips 28 are carried by the door structure and arranged to engage the top and bottom of said frame member to prevent circulation of air between the door and outer face of the frame member because such air, which is comparatively cold, would cause condensation on the face of the door if permitted to circulate adjacent the front panel of the door, such condensation being liable to cause serious damage in the cabinet structure by warping the outer door panel or loosening the joints in the door structure. The cold air is thus directed and caused to travel through the opening 29 between the ice chamber 15 and food chamber 14 therebelow.

A pan member 30 rests upon the partition 26, and the edges thereof are turned upwardly and lie adjacent the walls of the lining 31 within the chamber 15. A sheet metal casting 32 extends substantially around the supporting member 20 and one end 33 thereof extends over the front edge of the pan member for the purposes of covering the exposed upper front end of the pan member to direct condensation within the pan member and to

assist in positioning the pan member in a stationary relation.

Various changes in the structure may be made without departing from the spirit of 5 the invention as set forth in the appended claims.

What I claim is:

1. In a refrigerated food storage cabinet, a horizontal partition dividing said cabinet 10 into a refrigerating chamber and a refrigerated chamber, said cabinet having openings through the front wall to permit access to each of said chambers, and a single door closing the openings, said door having a groove 15 adapted to receive the front portion of said partition.
2. In a refrigerated food storage cabinet, a partition dividing the space within said cabinet into a refrigerating chamber and a refrigerated chamber, the front wall of said cabinet having an opening for each of the chambers, and a single door adapted to close the openings, said door extending into the 20 openings in the front wall of said cabinet.
- 25 3. In a refrigerated food storage cabinet having a refrigerating chamber and a refrigerated chamber, the front wall of said cabinet having openings to permit access to each of said chambers, a horizontal partition separating said chambers, and a single door
- 30 separating said chambers, and a single door

adapted to close the openings, said door having insulation means extending into said chambers when closed, said door being adapted to close both of the openings in a tightly sealed relation.

35

4. In a refrigerated food storage cabinet, a horizontal partition dividing said cabinet into a refrigerating chamber and a refrigerated chamber, said cabinet having openings to permit access to said chambers, and a single door for the openings, the insulation of said door being arranged in two spaced sections, the space between the insulating sections being adapted to receive a portion of said partition.

40

5. In a refrigerated food storage cabinet having a refrigerating chamber and a refrigerated chamber, the front wall of said cabinet having openings to permit access to each of said chambers, a horizontal partition separating said chambers, a single door adapted to close the openings, said door having insulation extending into said chambers, and a groove to receive said partition, said door being adapted to close the openings, and means 50 secured to the edges of said door for sealing the joint with said cabinet wall.

55

In testimony whereof I hereunto affix my signature.

WALTER H. WHITTIER.
